Herbert N. Hagel, Forest Hills, N. Y., assignor to
Everlast Pen Corporation, New York, N. Y., a
corporation of New York

Application March 23, 1950, Serial No. 8,723

Term of patent 14 years

(Cl. D74—17)

To all whom it may concern:

Be it known that I, Herbert N. Hagel, a citizen of the United States, residing at Forest Hills, in the county of Queens and State of New York, have invented a new, original, and ornamental Design for a Ball Pen, of which the following is a specification, reference being had to the accompanying drawing, forming a part thereof, wherein—

Fig. 1 is a side elevational view of a ball pen, showing my new design,

Fig. 2 is a rear elevational view; and

Fig. 3 is a rear elevational view thereof with the top removed.

I claim:

The ornamental design for a ball pen, substantially as shown and described.

HERBERT N. HAGEL.
